UNITED STATES PATENT OFFICE.

ALFRED JOHN CARLSON, OF MONTICELLO, MINNESOTA.

HAY-RACK.

1,147,371.

Specification of Letters Patent. Patented July 20, 1915.

Application filed May 1, 1912. Serial No. 694,494.

To all whom it may concern:

Be it known that I, ALFRED J. CARLSON, a citizen of the United States, residing at Monticello, in the county of Wright, State of Minnesota, have invented certain new and useful Improvements in Hay-Racks; and I do hereby declare the following to be a full, clear, and exact description of the invention, such as will enable others skilled in the art 10 to which it appertains to make and use the same.

This invention relates to improvements in hay racks.

The principal object of the invention is to 15 provide a separable rack for facilitating the rack being attached to or detached from a wagon body by one operator.

Another object of the invention is to provide a novel means for detachably connecting the rack sides to the wagon body.

A further object of the invention is to provide a rack which is composed of a minimum number of parts, is therefore simple in construction, and is cheap to manufacture.

With these and other objects in view, the invention consists in the construction and novel combination of parts hereinafter fully described, illustrated in the accompanying drawings and pointed out in the claim hereinafter appended; it being understood that various changes in the form, proportion, size and minor details of construction within the scope of the claim may be resorted to without departing from the spirit or sacrificing any of the advantages of the invention.

In the drawings, Figure 1 is a top plan view of a hay rack constructed in accordance with my invention. Fig. 2 is a detail view showing the hook and clip connection for 40 one of the inclined bars of the rack. Fig. 3 is an end view of the same.

Like reference numerals designate corresponding parts in all the figures of the drawings.

Referring to the drawings, the invention 45 comprises a wagon body which is designated as a whole by the reference letter A and this body consists of side sills 5—5, end sills 6—6 and an intermediate longitudinal sill 7. A

plurality of transversely disposed boards 8 50 are attached to the said sills and conjointly form the bottom of the hay rack, which is designated as a whole by the reference letter B. This rack includes a pair of side sections 9—9, each section consisting of a plurality 55 of spaced transverse bars 10 which are connected at their outer ends by means of longitudinal bars 11. The inner ends of the bars 10 are under-beveled for engagement with the wagon box A, and these beveled ends extend 60 transversely across said body, thereby disposing the opposite edges of said bars 10 at an upwardly inclined angle. The bars 10 of the sections are respectively disposed in staggered relation, and carried by the inner 65 ends of each of said bars is a forwardly extending hook 12. These hooks are caused to engage clips 13 or other attaching means which extend laterally from the sides of the body A and are in register with downwardly 70 inclined recesses 13, said recesses facilitating the attachment of the side sections to the wagon body or the detachment of said side sections from said body. It will furthermore be observed that by means of these 75 clips 13 and hooks 12, the sections are held in their proper position against accidental displacement. Secured to the opposite ends of each side of the body A are front and rear 80 socket elements, such as are shown at 15. Each end section of the structure includes a pair of spaced posts 18—18 which are connected by transverse strips 19—19. The posts 18 of the front end section are engaged 85 in the front socket elements 15, and the posts of the rear end section are engaged in the socket elements 16.

From the foregoing, it will be observed that the side and end sections may be readily disengaged from or attached to the wagon 90 body by a single operator, and that these sections when so attached will be securely retained upon the body against accidental displacement.

What is claimed is:

The combination with a wagon body including a floor having a spaced series of grooves formed in its side edges, a plurality

of clips connected to the side edges of the floor and disposed opposite the grooves, an opposed pair of upwardly inclined rack sections having their inner ends disposed in 5 overlapping relation to the body, and means carried by the inner ends of the rack sections and pivotally engaging said clips, the under faces of such inner ends being beveled and

bearing upon the floor of the body the entire width of such body.

10

In testimony whereof, I affix my signature, in presence of two witnesses.

ALFRED JOHN CARLSON.
